UNITED STATES PATENT OFFICE.

HAROLD PEROT KEEN, OF BELLEVUE, DELAWARE, AND DANIEL D. HUYETT, OF ARDMORE, PENNSYLVANIA.

THERMOSTATICALLY-OPERATED AMMONIA EXPANSION VALVE.

1,408,744.

Specification of Letters Patent.

Patented Mar. 7, 1922.

Application filed January 9, 1920. Serial No. 350,448.

To all whom it may concern:

Be it known that we, HAROLD PEROT KEEN and DANIEL D. HUYETT, citizens of the United States, residing at Bellevue, county 5 of New Castle, and State of Delaware, and at Ardmore, county of Montgomery, and State of Pennsylvania, respectively, have jointly invented a certain new and useful Thermostatically-Operated Ammonia Expansion Valve, of which the following is a specification.

The present invention relates to automatic expansion valves and has more especial relation to a thermostatically operated ammonia expansion valve for use in connection with refrigeration plants of the intermittent-absorption type.

A number of automatic expansion valves are upon the market which are actuated by ammonia pressure in the expansion coils of a refrigerating system. Such pressure is known in the art as "back" or "suction" pressure. The temperature of expanding ammonia bears a given, fixed relation to its pressure in the expansion coils. Valves of the above type are primarily reducing valves and are similar in action to the well known type of steam reducing valves. Ammonia passes to such a valve in the form of liquid anhydrous at receiver pressure and is reduced in the expansion coils to a low pressure, corresponding to the temperature desired. Experience dictates, however, that valves actuated by ammonia pressure are not adaptable to the intermittent-absorption type of refrigerating apparatus for the reason that "back" or "suction" pressure varies from 25" vacuum to 30 pounds pressure. At the beginning of a refrigeration period 40 the suction pressure is low while at the end of a period this pressure is high.

The leading object of the present invention may be said to be to provide an expansion valve controlled directly by temperature 45 of the medium being cooled, as for instance a cold-storage room, brine tank, water cooler or the like. A further object is to provide a thermostatically operated expansion valve whereby when temperature of the air in the medium to be cooled increases slightly above 50 desired temperature a thermostat opens the expansion valve thus allowing liquid ammonia to flow to the expansion coils, and when temperature has been reduced to de-

sired point the thermostat closes the expansion valve to interrupt the flow of liquid ammonia. A further object is to provide an expansion valve constructed to open and close in an evenly balanced manner irrespective of the pressure present at the ammonia inlet and outlet. A still further object is to provide an ammonia expansion valve in which friction causing parts are reduced to a minimum. Other and further objects reside in the provision of a certain 55 new and novel arrangement and combination of parts for commercially bettering the 60 class of valves under consideration.

The invention consists of the improvements hereinafter described and finally 70 claimed.

The nature, characteristic features and scope of the invention will be more fully understood from the following description taken in connection with the accompanying 75 drawings forming part hereof, and in which:

Fig. 1, is a view in elevation of the thermostatically operated ammonia expansion valve embodying features of the invention. 80

Fig. 2, is a detail view, in central section, of the valve parts detached from the operating medium.

Fig. 3, is a detached view, in elevation of 85 the yoke shown in Fig. 2.

Fig. 4, is a detail view, in section, of the ammonia charging valve.

Fig. 5, is a view, in elevation, illustrating one mode of employing the valve of the invention, and

Fig. 6, is a similar view illustrating another mode of employing the valve.

For purpose of illustrating our invention, we have shown in the accompanying drawings forms thereof which are at present preferred by us, since the same have been found in practice to give satisfactory and reliable results, although it is to be understood that the various instrumentalities of which our invention consists can be variously arranged 95 and organized and that our invention is not limited to the precise arrangement and organization of the instrumentalities as herein shown and described.

In the drawings 10 designates a valve casing which is provided with an ammonia liquid inlet 11 and an outlet 12 leading to expansion coils *a*. The casing 10 is flanged

at each end, a plate 13 being bolted to one flange and a bonnet 14 being bolted to the other. Within the casing and preferably formed integral therewith is a neck 15 having a passage therein parallel and in register, at one end, with inlet 11. The other end is in communication with a passage 16 at right angles thereto and which is extended through a member 17 having a valve-seat 18 therein for accommodating a valve-spindle 19. This member 17 is removably fixed to neck 15 and has a passage 20 therethrough at right angles to passage 16 and communicating therewith. A yoke 21 is located with-
in casing 10 and is adapted to straddle neck 15 and member 17 at right angles thereto and adjustably carries at one end the valve-spindle 19. The other end of yoke 21 is guided by a pin and slot connection 21' with-
in an opening in one end of casing 10. Valve-spindle 19, traveling back and forth with respect to its valve seat, serves to guide the other end of said yoke. Sufficient play between parts is allowed in order that the valve-spindle be self-centering. Clamped between the plate 13 and one end of casing 10 is a diaphragm 22, the casing end and plate being recessed to permit movement of the diaphragm which is thermostatically operated in a manner to presently appear. Clamped between the opposite end of casing 10 and the bonnet 14 is another diaphragm 23 which is directly opposed by a spring 24 contained within said bonnet. The tension of spring 24 may be regulated by screw 25. The ends of yoke 21 abut with diaphragms 22 and 23 respectively so that inward movement of diaphragm 22 serves to move valve-spindle 19 away from its seat against the action of spring 24 which normally tends to hold said spindle against said seat.

A description will now be given of the thermostatic control for operating diaphragm 22. 26 designates a seamless, drawn steel tube exteriorly provided with a plurality of disc-like fins 27 of copper gauze soldered thereto. One end of tube 26 is in communication with a coil 28 formed of seamless steel tubing which in turn communicates with an opening 29 passing through plate 13 and is in register with the recessed portion thereof opposite the sensitive, steel diaphragm 22. Tube 26 and coil 28 are filled with liquid anhydrous ammonia which is fed through a manually operated charging valve 30' carried by the free end of tube 26. This liquid, when heated to 95°, exerts a pressure of about 185 pounds per square inch and if reduced to zero exerts a pressure of only 15 pounds. At other temperatures this liquid exerts a corresponding pressure according to the physical properties of anhydrous ammonia. Pressure as generated in the thermostat serves to operate the diaphragm 22.

The operation of the above described thermostatically operated ammonia expansion valve may be described as follows:—When the device is installed, for instance in a cold-storage room, a liquid ammonia connection is made between an intermittent-absorption refrigeration apparatus (not shown) and the valve inlet and the valve outlet connected to ammonia expansion coils of such apparatus. The return or suction line of the coils are connected to the usual generator-absorber. The cold-storage room temperature being warm at this time causes the thermostat to exert considerable pressure upon dia- 70 phragm 22 with the result that valve-spindle 19 is caused to recede to its full extent from its seat. Liquid ammonia, under such conditions, expands into the coils of the refrigerating apparatus and refrigeration takes place with consequent lowering of room temperature. With lowering of room temperature, pressure in the thermostat decreases with the result that spring 24 causes dia- 75 phragm 23, through yoke 21, to move valve-spindle 19 against its seat, thus cutting off 80 the flow of liquid ammonia to the coils. Obviously as rise and fall of room temperature takes place from time to time the thermostat is so affected that liquid ammonia is permitted or denied passage through the 85 expansion valve. In this connection it is to be observed that the fins upon the tube of the thermostat function to absorb and radiate heat so that a rapid "heat interchange" 90 is made between the ammonia within the tube and air surrounding the tube thus adding to the sensitiveness of the thermostat. The purpose of the coiled tubing is to pre- 95 clude "frost-creep" between the expansion valve and thermostat. When refrigeration is taking place, the valve is covered with frost reaching a temperature much below that of the air or other substance to be cooled. The coiled tubing is of such length that the 100 valve temperature will not pass to the thermostat. Otherwise such temperature would tend to lower the temperature of the anhydrous ammonia contained within the thermostat with the result that the valve would 105 improperly function.

With the initial reduction of room temperature, with the valve wide open as described, there is a tendency for too much liquid ammonia to pass to the coils with the result that a certain percentage of refrigerant is wasted before room temperature becomes low enough to affect the thermostat. Currents of warm air, due to various causes, may also be present in the room which also tend to cause the valve-spindle to be unduly removed from its seat. To overcome these objectionable features we have designed a stop-device which may be set to permit a maximum flow of liquid suitable for a given size expansion coil or refrigerating-box.

Having screw threaded relation with adjusting screw 25 is a stem 30 which passes loosely through the spring retainer 31 and abuts against the follower 32 of diaphragm 23. 5 The spring is first adjusted for desired temperature by screw 25 and stem 30 is screwed against the follower 32 until the valve-spindle 19 abuts against its seat. Stem 30 is then loosened to obtain the desired maximum valve opening, the screw 25 being fixed to place by means of lock-nut 33.

In practice a very slight movement of the valve-spindle from its seat will permit of considerable refrigeration. The maximum movement in largest types of intermittent absorption refrigeration apparatus does not exceed a few thousandths of an inch. The maximum movement of the present diaphragm and valve-spindle is about one six- 20 tenth of an inch. As the opening through the valve-seat is relatively small there is a tendency for said seat to clog with fine particles of matter suspended in the liquid ammonia. If the valve-spindle is withdrawn 25 to its full extent, however, this foreign matter may be readily purged from the valve-seat. This may be accomplished through the instrumentality of the stop-device just described.

30 We have shown in the drawings several ways of employing the thermostat in connection with the expansion valve. In Fig. 5 the thermostat is shown exposed either to air, brine or other liquid to be cooled. In 35 Fig. 6, the copper gauze fins are dispensed with and the tube contained within the ammonia suction line which carries expanded vapors from the ammonia coils to the generator-absorber. When such vapors reach a 40 predetermined low temperature the valve-spindle is seated to close the flow of vapors. As the vapors rise in temperature the valve-spindle withdraws from its seat. By such arrangement, with proper proportioning of 45 the expansion coils and proper adjusting of spring in the bonnet, temperature of a refrigerating compartment may be regulated as desired.

It will now be apparent that we have devised a novel and useful construction which 50 embodies the features of advantage enumerated as desirable in the statement of the invention and the above description and while we have in the present instance shown and 55 described the preferred embodiment thereof which has been found in practice to give satisfactory and reliable results, it is to be understood that the same is susceptible of modification in various particulars without 60 departing from the spirit or scope of the invention or sacrificing any of its advantages.

What we claim is:—

1. In apparatus of the character stated the combination of expansion coils, an expansible fluid feed line to said coils, an expansion valve located in said line, a thermostat-tube containing expansible fluid responsive to changes in temperature of a system being cooled and closely coiled piping interposed between and communicating with the expansion valve and said thermostat-tube said piping serving as an insulator to prevent low temperature being conducted from said valve to said thermostat-tube.

2. In apparatus of the character stated the combination of expansion coils, an expansible fluid feed line to said coils, an expansion valve located in said line, said valve being equipped with spaced diaphragms arranged to be balanced against the pressure of said expansible fluid, said diaphragms having valvular means operatively connected therebetween, means for causing one of said diaphragms to maintain said valvular means closed, a thermostat-tube containing expansible fluid responsive to changes in temperature of a system being cooled and closely coiled piping interposed between and communicating with the expansion valve and said thermostat-tube said piping serving as an insulator to prevent low temperature being conducted from said valve to said thermostat-tube, said thermostatic means functioning to operate the other of said diaphragms for opening said valvular means.

3. In apparatus of the character stated the combination of expansion coils, an expansible fluid feed line to said coils, an expansion valve located in said line said valve being equipped with spaced diaphragms arranged to be balanced against the pressure of said expansible fluid, said diaphragms having valvular means operatively connected therebetween, means for causing one of said diaphragms to maintain said valvular means closed, a thermostat-tube containing expansible fluid responsive to changes in temperature of a system being cooled and closely coiled piping interposed between and communicating with the expansion valve and said thermostat-tube said piping serving as an insulator to prevent low temperature being conducted from said valve to said thermostat-tube, said thermostatic means functioning to operate the other of said diaphragms for opening said valvular means, and means for obtaining a predetermined opening of said valvular means.

In witness whereof we have herewith signed our names.

HAROLD PEROT KEEN.
DANIEL D. HUYETT.
